UNITED STATES PATENT OFFICE.

GEORGE FRANK EVANS, OF SOMERVILLE, MASSACHUSETTS.

WIRE-DRAWING MACHINE.

SPECIFICATION forming part of Letters Patent No. 448,215, dated March 17, 1891.

Application filed September 3, 1890. Serial No. 363,821. (No model.)

To all whom it may concern:

Be it known that I, GEORGE FRANK EVANS, a citizen of the United States, residing at Somerville, in the county of Middlesex and State of Massachusetts, have invented certain new and useful Improvements in Wire-Drawing Machines; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to improvements in wire-drawing machines, in which a continuous length of wire is successively passed through a series of dies, which gradually reduce it until the proper size is produced.

20 My improvements relate particularly to the mechanism by which variable motion is imparted to the wire-drawing drums or cylinders about which the wire is passed in order to pull it through the die with which it operates. This mechanism, more fully hereinafter described, enables the speed of each wire-drawing drum to be regulated just as may be desired and while the machine is in motion—an important and desirable feature.

25 The drawings represent in Figure 1 a plan of a wire-drawing machine embodying my improvements. Fig. 2 is a side elevation, much enlarged, of the mechanism for varying the speed of the wire-drawing drums. Fig. 3 is a transverse section of the machine, showing this same mechanism enlarged.

In Fig. 1 the general features of a wire-drawing machine of the class above premised are represented as follows: 2 is the frame of 30 the machine, upon which the various co-operating parts are mounted. These parts consist, primarily, of a main driving-shaft 3, with fast and loose pulleys. This shaft extends longitudinally of the machine-frame, and is 35 provided with a series of cone-pulleys 4' 4² 4³ 4⁴. In parallelism with the main shaft are arranged a series of counter-shafts 5' 5² 5³ 5⁴. The latter, furnished with a series of cone-pulleys 6' 6² 6³ 6⁴, are positioned reversely of 40 those on the main shaft and to correspond with the position of said driving-pulleys.

Loosely encircling each driven pulley 6', &c., is placed an endless band 17, which is adapted to pass between and be gripped by the pair of reversely-positioned cone-pulleys 4' 6' 4² 6², which 55 are non-contiguous. Thus each driven pulley and its counter-shaft may be adjusted in its rotation independently of any other but corresponding counter-shaft. This is effected by shifting the position of the belt endwise 60 of the driving-pulley by mechanism not here shown, since it is immaterial to my present invention. However, such mechanism is fully described in Letters Patent issued in my name on the 6th day of December, 1887, and numbered 374,296. 65

Along the front side of the machine are grouped the reducing-dies 7 7' 7², (shown as fixed to the machine-frame,) and between them are arranged a series of wire-drawing 70 drums 8' 8² 8³, about which the wire is given one or more turns. Each die has a co-operating drum, and the entire series is in longitudinal adjustment, so that the wire 20 shall move in a proper and continuous direction 75 in its passage through the machine. To operate these drums and regulate their movements according to the ductility or other variable conditions which occasion faster or slower rates of travel in the wire, and to enable such adjustments to be effected while the machine is at work, I have mounted each wire-drawing drum on short shafts 9' 9² 9³ transversely of the machine. The several 80 drums are attached to the front projecting ends of their respective shafts, while at the rear end portion of said shafts are affixed worm-gears 10' 10² 10³, aligned above the counter-shafts 5' 5² 5³, which are here equipped with worms 12' 12² 12³, the latter engaging 90 with their respective gears, whereby the variable adjustable speed of the counter-shafts is transmitted to the wire-drawing drums. Consequently, the movement of the latter are regulated individually, as the conditions or 95 circumstances require.

What I claim is—

1. In a wire-drawing machine, the combination, with a series of driving cone-pulleys revolving at uniform speed and a series of driven cone-pulleys at varying speed, of a series of wire-drawing drums, their transverse shafts, 100

and the series of worm-gears and worms which interconnect each shaft of the driven pulley with the shaft of the wire-drawing drums, substantially as and for the purposes specified.

5 2. The combination, with a prime motor, a main shaft, a series of cone-pulleys thereupon having uniform speed, a series of wire-drawing drums, and their actuating-shafts, with variable speed, of a series of cone-pulleys on 10 their respective counter-shafts, also at variable speed, the endless band gripped between the two sets of cone-pulleys, and a worm-gear and worms which interconnect the shafts of the wire-drawing drums and the driven cone-pulleys, substantially as described.

15 3. In combination with a series of fixed reducing-dies, a series of wire-drawing drums at variable speed, their independent shafts provided with worm-gears, the respective 20 counter-shafts furnished with a worm and a driven cone-pulley, and the main shaft with the series of driving-cone pulleys which actuate the driven cones by a loose endless band

which passes between each pair of pulleys, substantially as stated.

4. In a wire-drawing machine, a series of fixed reducing-dies, the series of transverse shafts at variable speed equipped with a wire-drawing drum, a series of counter-shafts furnished with driven cone-pulleys, and a main 30 shaft having a series of reversely-positioned driving cone-pulleys, combined with a worm-gear, a worm, and a loose endless band, the worm-gear and worm engaging to interconnect the shafts of the wire-drawing drums 35 with those of the driven cone-pulleys, while the endless band adjustable endwise between the two sets of cones serves to operate the driven set and imparts variable speed thereto, substantially as specified and set forth.

40 In testimony whereof I affix my signature in presence of two witnesses.

GEORGE FRANK EVANS.
